UNITED STATES PATENT OFFICE.

BURTON W. KENDALL, OF EAST ORANGE, NEW JERSEY, ASSIGNOR TO WESTERN ELECTRIC COMPANY, INCORPORATED, OF NEW YORK, N. Y., A CORPORATION OF NEW YORK.

BEST AVAILABLE COPY SECRET SIGNALING.

Original application filed December 23, 1920, Serial No. 432,680. Divided and this application filed June 19, 1925. Serial No. 38,129.

To all whom it may concern:

Be it known that I, BURTON W. KENDALL, a citizen of the United States of America, residing at East Orange, in the county of 5 Essex and State of New Jersey, have invented certain new and useful Improvements in Secret Signaling, of which the following is a full, clear, concise, and exact description.

This invention relates to secret signaling 10 and particularly to secret transmission of speech or intelligible sounds by electrical waves.

An object of the invention is to provide a method of and system for secret signaling.

15 Another object of the invention is to provide a method of transmitting audible frequency waves which are unintelligible as speech but from which intelligible speech waves may be derived.

20 One feature of the invention relates to modulation of carrier waves by waves of speech frequency range representing speech but unintelligible as such when detected by ordinary methods.

25 An additional feature of the invention is the provision of a radio telephone system which is secret to those not provided with a special receiving apparatus.

The present application is a division of 30 my copending application Serial No. 432,680, filed December 23, 1920.

Ordinary telephone transmission is accomplished by transmission of electric currents which correspond in their instantaneous amplitudes and frequencies to the simultaneous amplitudes and frequencies of the different sound wave components comprised in articulate speech. The essential speech frequencies may be considered to range from 35 about 200 cycles to 2200 cycles. Accordingly, articulate speech is intelligible as such when it comprises the proper frequency components with their accompanying harmonics 40 of the proper relative intensities. Any operation which destroys these essential relationships makes it impossible to receive intelligible speech until the relationships have been restored.

45 The present invention relates to a method 50 of and means for changing the frequencies of each of the components of speech currents in such manner that, although the changed speech currents will extend over a frequency 55 bandwidth and based on the number of speech components, the bandwidth will be less than the bandwidth of the original speech currents.

range as wide as that of the original speech waves, the essential relationships for intelligible speech have been destroyed. This further involves transmission of the changed speech waves and restoration of the essential speech relationships at a receiving station.

According to the present invention, speech 60 waves are combined with a single wave of audio frequency to produce a modulated audio frequency wave with two side bands, each having a frequency range co-extensive with that of the original speech currents. 65

One of these bands includes the sum of the frequencies of the speech current components and the audible wave component, the other, the difference of the audible wave frequency and the speech component frequencies. 70 One of the two bands is selected and may be used to transmit speech energy, although the essential speech frequency relationships have been destroyed so that the

transmitted energy, if directly applied to a 75 receiver, produces merely an unintelligible noise. Preferably, the difference frequency side band is selected for transmission since in this band the frequencies of the individual speech components have been inverted. If 80

the audible wave combined with the speech wave has a frequency at approximately the upper limit of the essential speech frequency range, the difference frequency or inverse 85 frequency band will occupy the same absolute range of frequencies as the original speech.

Increasing frequency in the speech will be represented by decreasing frequency in the inverse frequency speech band and vice versa. The unintelligible audible band 90 thus obtained may be transmitted directly as in the case of simple electric telephony but in accordance with the invention to be claimed in this divisional application the unintelligible audio band is caused to modify 95 a carrier wave for either radio or guided circuit transmission.

As used herein, the term "combiner" is applied to devices of the character of modulators or detectors having the non-linear 100 relation between applied input electromotive force and resulting available output current commonly denoted by "curved characteristics". Such a device operates to produce in its output circuit, sum and difference frequency components of the sinusoidal 105 signals received at its input terminals. 110

emotive force frequencies simultaneously applied to the input circuit. In this definition input and output circuits are used merely to indicate the respective elements 5 upon which the sinusoidal electromotive forces are impressed and from which the sum and difference frequency components are derived and may, therefore, be one and the same circuit. The capital letters A, C, 10 F and M as employed in the drawing are used to denote amplifier, combiner, filter and modulator respectively.

In the drawing, Fig. 1 illustrates a transmitting system embodying certain features 15 of the invention in which speech currents from an ordinary telephone line are utilized to produce an equally extensive range of inverse frequency currents which lie within the normal speech frequency range 20 but are unintelligible as speech when supplied to an ordinary receiver; Fig. 2 illustrates a receiving station suitable for cooperating with the transmitting station of Fig. 1; Fig. 3 shows diagrammatically the 25 invention applied to a radio transmitting system, and Fig. 4 shows a radio receiving station suitable for cooperating therewith.

Figs. 1 and 2, respectively illustrate a 30 transmitting and a receiving station which are located at the opposite terminals of a line 3' the transmitting station having an outgoing channel only and the receiving station having an incoming channel only. In 35 practice, each station would usually be arranged for two-way transmission and would accordingly have both an incoming channel and an outgoing channel connected to line 3' by balanced hybrid coils in the usual 40 manner.

Referring to Fig. 1, the outgoing channel 6 is shown as comprising potentiometer 16, low pass filter 18, balanced modulator M, vacuum tube oscillator 20 and amplifier 21, 45 and a second low pass filter 22 similar to filter 18. The low pass filters are of the general type disclosed in Campbell Patent 1,227,113, dated May 22, 1917, and are so designed as to transmit with practically uniformly negligible attenuation, currents of 50 all frequencies less than a fixed cut-off frequency, as for example, 2200 cycles, while substantially extinguishing all currents of higher frequencies. The oscillator 20 comprises the well-known three-element electron discharge device having a frequency determining tuned loop consisting of inductance 24 and variable capacity 25 in its plate-filament circuit and having its grid-filament circuit coupled by an inductance 60 26 to inductance 24 in well-known manner to enable the device to produce continuous oscillations. The grid-filament circuit of thermionic amplifier 21 is connected directly to that of oscillator 20, which ac-

cordingly impresses the generated oscillations upon the amplifier, which in turn, impresses amplified oscillations across the variable resistance 27. The amplifier 21, oscillator 20 and balanced modulator M are each supplied with space current from the common source 28 through choke coils 29 which exclude the oscillatory circuit, thus preventing high frequency coupling to the common space current supply. The various filamentary cathodes of the modulator, oscillator and amplifier may likewise receive heating current from a common source, but individual sources have been shown to simplify the drawing. The modulator M is of the balanced type disclosed in Hartley Patent 1,419,562 dated June 13, 1922 and, as is well known, serves to pass the modulated side bands or sum and difference frequency components of the currents impressed on the input circuit while substantially preventing transmission of unmodulated currents corresponding to the impressed waves. If the oscillator 20 supplies a wave of 2200 cycles frequency, the two side bands produced by modulation with the speech currents will both be within the audible range, and the lower side band will occupy substantially the same range as the original speech, but will be unintelligible because it consists entirely of inverse frequencies. For example, the frequencies 800, 1000 and 1200 of the original speech components will have become inverse frequencies 1400, 1200 and 1000, respectively. An increasing pitch tone of speech will become an unintelligible decreasing pitch noise in the inverse frequency band. The filter 22 suppresses the upper side band and permits transmission of only the inverse frequency band.

The receiving channel in Fig. 2 comprises substantially the same general arrangement of apparatus as in the transmitting channel of Fig. 1 with the addition of a receiving amplifier, namely, an oscillator and a second amplifier, which are connected to supply oscillations to the receiving amplifier output circuit, a balanced combining device, and a low pass filter. These elements correspond in tuning to those of the outgoing channel of Fig. 1, and are designated by reference characters similar to those designating the corresponding elements in that channel. The inverse frequency speech currents as received from the transmitting station are amplified by the receiver amplifier, and may be combined in the balanced combining device 19' with oscillations of say, 2200 cycles frequency from the oscillator 20' to produce two side bands, the lower of which is intelligible speech current. The speech currents are selected and transmitted to the telephone circuit 2' by the low pass filter 18' which suppresses the upper side band. The balanced combining device M in the outgoing channel

in Fig. 1, as already explained, prevents transmission to the line 3' of ordinary speech currents. The balanced combining device C in the incoming channel of Fig. 2 5 similarly prevents transmission of the inverse frequency currents to the telephone line 2'. It follows that while both lines 2' and 3' transmit the same frequency range of currents, the currents of line 2' are intelligible in any ordinary receiver, while those of line 3' are not. The line 3', since it transmits speech frequencies, may be adapted for ordinary speech transmission as, for example, a loaded line.

15 In Fig. 3, the elements 18, 20, M and 22 may be the same as the corresponding elements of Fig. 1. The filter 22 feeds into a second modulator M' of any suitable type which is supplied also by a radio frequency 20 wave from an oscillator O', which may be of the same type as oscillator 20, but its constants are adjusted so that it produces a wave of a frequency suitable for radiation.

In Fig. 4, the elements A, C, 20' and 18' 25 may be the same as the corresponding elements of Fig. 2. Coupled between the antenna and the amplifier A is a demodulator or combiner C' of any suitable type.

The operation of the system shown in 30 Figs. 3 and 4 is as follows:

The filter 18 of Fig. 3 receives a speech wave from any desired speech-transmission circuit and limits the frequencies transmitted to some definite range such as 0 to 2200 35 cycles. This band of frequencies modulates at M, a sustained wave of 2200-cycle frequency from the source 20, and the resulting lower side band comprising unintelligible inverted speech components of speech frequency range 40 are selectively passed through the filter 22 to the radio-transmitting modulator M'. Here the inverted speech band modulates the wave of radio-frequency from the source O', and the resulting modulated wave is radiated from the antenna shown.

If the wave so radiated were received on an ordinary detecting set, it would yield only unintelligible noises, since the modulating wave comprises only inverted speech components. However, the wave when received on the antenna of Fig. 4, is detected at C', and after amplification is treated in exactly the same manner as at the receiving terminal in Fig. 2, that is, the detected inverted speech 50 band is combined at C with a wave of frequency near the upper limit of the band, say 2200 cycles, from source 20' and the resulting lower side band, which is normal speech 55 is passed through filter 18' to the telephone receiver so that understandable speech is received.

Preferred forms of embodiment of the invention, containing however, limitations unessential to the invention itself, have been illustrated and described by way of example.

The scope of the invention is limited only by the appended claims.

What is claimed is:

1. The method of secret radio telephony which comprises producing an inverted speech frequency band occupying approximately the same absolute frequency range as normal speech, modulating a radio wave in accordance with said inverted frequency band, and radiating said modulated waves. 75

2. The method of transmission of waves comprised of a band of frequency components which consists in interchanging the frequency positions of the various components while keeping the resultant frequencies within substantially the same limiting frequencies as the original band, and modifying a carrier wave with the resultant frequency band. 80

3. The method of telephony comprising inverting the frequency order of speech waves to produce waves whose components occupy frequency positions corresponding to the difference between a constant frequency and the speech frequencies before inversion, the inverted frequency waves lying between substantially the same frequency limits as the original speech, and modulating a carrier wave by the inverted speech 85 waves. 90

4. The method of telephony comprising transmitting a carrier wave modulated by waves of approximately the speech frequency range, said waves being speech waves with their normal frequency order inverted, receiving said modulated carrier wave, detecting said wave to produce waves of speech frequency range therefrom, and inverting the last-mentioned waves of speech frequency range. 100 105

5. In a signaling system, means to invert the frequency order of waves to be transmitted while keeping the inverted frequency waves within substantially the same limiting frequencies as the original signals, and means to modulate a carrier wave in accordance with the inverted frequency waves. 110

6. In a carrier telephone system, means to invert the normal frequency order of speech waves to be transmitted while keeping the inverted waves within the normal speech frequency range, and means to modulate a carrier wave in accordance with the inverted speech waves. 115

7. In a carrier telephone system, means to derive from speech waves a band of waves occupying substantially the speech frequency range but representing the frequency inverse of normal speech, means to modulate a carrier wave by said band of inverted frequency waves, means for transmitting the waves so modulated, means for receiving and detecting said wave to produce speech frequency components therefrom, means for inverting the speech frequency components so pro- 120 125 130

duced and a telephone receiver for responding to the last mentioned inverted components.

8. The method of transmission of waves comprised of a band of speech frequency components which consists in inverting each of the speech frequency components of said band to produce an unintelligible inverted frequency band occupying a frequency range overlapping that of the original band, modulating a carrier wave in accordance with said inverted frequency band, and radiating the modulated wave.

9. The method of transmission of waves comprised of a band of speech frequency components which consists in inverting the speech frequency components of said band so as to produce a resultant inverted speech frequency band occupying a frequency range overlapping that of the original speech, modulating a carrier wave with said inverted band, transmitting the modulated wave, receiving the modulated carrier wave, detecting said wave to produce waves of the speech frequency range therefrom, and inverting the last-mentioned waves.

10. In a carrier telephone system, means to invert a band of speech frequencies to produce an unintelligible inverted frequency band occupying a frequency range overlapping that of the original band, means to modulate a carrier wave with said inverted frequency band, and means to radiate the modulated wave.

11. In a carrier telephone system, means for generating a carrier wave, means for producing an inverted speech frequency band occupying a frequency range overlapping that of the original speech, means to modulate said carrier wave with said inverted speech frequency band, means for transmitting the wave so modulated, means for receiving and detecting said modulated wave to produce speech frequency components therefrom, means for inverting the speech frequency components so produced, and a receiver for responding to the last-mentioned components.

In witness whereof, I hereunto subscribe my name this 16th day of June A. D., 1925.

BURTON W. KENDALL.
